UNITED STATES PATENT OFFICE

2,613,613

STEAM LOCOMOTIVE, INCLUDING
INDIVIDUAL AXLE DRIVES

Hans Nyffenegger, Winterthur, Switzerland, assignor to Schweizerische Lokomotiv- und Maschinenfabrik, Winterthur, Switzerland

Application March 7, 1945, Serial No. 581,407
In Switzerland December 18, 1943Section 1, Public Law 690, August 8, 1946
Patent expires December 18, 1963

1 Claim. (Cl. 105—115)

1. This invention relates to locomotives including individual axle drives.

Proposals and actual constructions of steam locomotives are known in which the driving axles are independently driven by steam engines. However, all such constructions, whether with or without transmission gear, are not fully satisfactory for various reasons.

In one of these proposals the steam engines are arranged between the side girders of the main frame of the locomotive, in consequence whereof, access to the engines is encumbered. In a known construction the accessibility to the engines is adequate, due to the arrangement of multi-cylinder steam engines on auxiliary frames on both sides of the locomotive exteriorly of the main frame for cooperation with a transmission gear drive intermediate of the side girders of the main frame, but the assembly is nevertheless complex. Further, the provision of separate flexible couplings between the crank shafts of the engines and the pinion shaft is indispensable.

In another known practical application, two cylinder steam engines with the cylinders arranged in V-shape are disposed on the frame exteriorly beyond the wheels and are connected with the associated wheel and axle structure by means of a flexible coupling. In this arrangement the speed of revolution of the engine depends exclusively upon the driving wheel diameter and the driving speed, due to the absence of a transmission gear. Further, the driving axle performance is restricted in this arrangement for the reason that, with a view to avoiding excessive wheel bases, it is imperative to associate only one steam engine with each driving axle so that alternate engines are arranged on the right and left hand side of the locomotive respectively. If then, in an effort to raise the engine speed a transmission gear is interposed between the motor and the driving axle the remaining available space for the accommodation of the engine is limited to an objectionable extent. The above-mentioned difficulties cannot be eliminated by the use of high steam pressures either. Generally speaking, considerable difficulty is encountered in building steam locomotives including individual axle drives from the point of view of satisfying all the contradictory requirements in regard to critical speed, compensation of movable masses and uniformity of driving torque.

In the arrangement according to the present invention, the commonly known drawbacks are eliminated as well as the abovesaid difficulties in that each engine crank-case is rigidly secured to

the transmission gear casing, the transmission-gear pinion shaft is journaled solely adjacent its ends in the said casing and at its ends are rigidly but disconnectably coupled to the piston-engine crank-shafts.

Two embodiments of the present invention are illustrated, by way of example only, in the accompanying drawings, in which

Fig. 1 shows the left-hand portion of the first example, including four engine cylinders and a frame disposed inside the driving-wheel planes,

Fig. 2 a schematic view of said drive in side elevation;

Fig. 3 shows a modified detail of Fig. 1, and

Fig. 4 shows the left-hand portion of the second example including six cylinders and a frame disposed outside the driving-wheel planes.

Referring to Fig. 1, the crank shaft 1 of one of the two two-cylinder steam engines, which are symmetrically arranged relative to the longitudinal middle plane of the locomotive, is mounted only in one bearing 2 in the outer wall of the crank casing 3, whereas the inner end of the crank shaft which terminates in a crank arm 15 constituting a coupling flange 4 is rigidly connected with a coupling flange 5 on a pinion shaft 8 which is mounted in the gear casing 7 at 6. The pinion shaft 8 is in form of an extraordinarily rigidly built hollow shaft the central portion of which carries a centrifugal mass 9 adjacent to both end faces of which a pinion 10 is shrunk on the hollow shaft. The bearings 6 which are symmetrically arranged on the hollow shaft relative to the middle plane of the locomotive are, however, not disposed immediately at the side of the pinions 10 but remote therefrom at both ends of the pinion shaft 8 directly on the side of the coupling flanges 5. The pinion shaft is parted in the middle along a plane 11 and its two halves are interconnected by means of screws (not shown).

The pinions 10 on the shaft 8 are in mesh with spring mounted gear rims of the gear wheel gears 12 which are arranged on a countershaft 17 (Fig. 2) which is mounted in the gear casing 7. Numerical 12a (Figs. 1 and 4) indicates two tangentially arranged springs providing the said spring-mounting. This countershaft carries a further gear wheel 13 which cooperates with a large hollow gear wheel 14 which surrounds the driving axle and is also mounted in the gear casing 7. The hollow gear 14 is connected with the driving axle 15 by means of a flexible coupling which is not shown in detail in the drawings.

The construction shown in Fig. 1, although

having only a few cylinders, in the number of four, per driving axle, results in a driving torque which comes up to the requirement put on uniformity of torque in practice, especially at high running speeds at which the smoothing action of the centrifugal mass 9 is most effective. For the same purpose the engine cranks of an arrangement as shown in Fig. 1 are, advantageously, relatively offset by 180° or 135° at least. The crank shafts of the two engines are relatively offset by 90°. This construction further lends itself for a maximum possible equalization of movable masses. Due to the rigid construction of the pinion shaft 8, this shaft is free from torsional oscillations within the range of computed running, particularly free from the feared counter oscillations resulting from conjoint oscillation by the two associated steam engines.

With this arrangement the pinion shaft can be satisfactorily supported by bearings which are situated at a great distance apart so that the inner crank shaft bearings can be omitted by virtue of the firm connection between the pinion shaft and the two crank shafts. By this means the simplest form is obtained for the two steam engines which apart from this have an improved degree of mechanical efficiency on account of the reduced number of crank shaft bearings. For improving the course of the driving torque curve of the steam engine the central crank arm 18 can be given the form of an additional centrifugal mass 19, as shown in Fig. 3.

The arrangement illustrated in Fig. 4 differs from that shown in Fig. 1 in that, apart from the employment of an exterior frame 20 instead of an interior frame, three cylinders can be provided instead of two for the steam engines on opposite sides of the locomotive the efficiency of each of which is 50% greater than that of the engines formerly used.

In accordance with the greater number of cylinders the resulting driving torque is more regular compared with that produced by 2 x 2 cylinders. The engine cranks of the three-cylinder engines are relatively offset by 120°. Furthermore, the pinion shaft is composed of three parts joined together by screw connections. If the pinion 10 is in form of a toothed rim and

is shrunk on the hollow shaft 8' this arrangement of the pinion shaft permits of making the flanges 4, 5 of a larger diameter than if the shaft were not subdivided at all, for the reason that then the diameter of these flanges needs no longer to be smaller than the inner diameter 10' of the toothed rim of the pinion. Above all, in this exterior frame arrangement, for the wheel and axle structures 15, advantageously, roller bearings can be arranged at 21 instead of friction bearings.

I claim:

In a steam locomotive having a main frame, a plurality of driving wheel-and-axle sets mounted in said frame, a drive unit for each said set, said unit including two multi-cylinder piston engines having each a crank case and a crank shaft situated exteriorly of said main frame on either side thereof, transmission gearing common to both crank shafts for transmission of torque from the crank shafts to the corresponding wheel-and-axle set, a gear casing rigidly secured to said main frame, a pinion shaft having opposite ends rigidly coupled each with one of said crank shafts, said gearing including a primary pinion on said pinion shaft, a gear wheel surrounding the driving axle in driving connection with said pinion, and a flexible torque transmission coupling between said gear wheel and the driving axle, said crank cases of each driving unit being directly secured to the respective transmission gear casing.
